UNITED STATES PATENT OFFICE.

MATTHEW B. KENDRICK, OF NEWPORT, KENTUCKY, ASSIGNOR OF ONE-HALF TO FRANK B. RAMPE, OF CINCINNATI, OHIO.

TIE-HOLDING COLLAR.

SPECIFICATION forming part of Letters Patent No. 611,578, dated September 27, 1898.

Application filed May 9, 1898. Serial No. 680,129. (No model.)

To all whom it may concern:

Be it known that I, MATTHEW B. KENDRICK, a citizen of the United States, residing at Newport, in the county of Campbell and State of Kentucky, have invented certain new and useful Improvements in Tie-Holding Collars; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to that class of collars which are used about the neck by men and women and adapted to be buttoned to a garment and with which a necktie is used; and it consists in a standing collar of new and novel 20 form of construction, providing means whereby the band of the tie around the collar is retained in its proper position and prevented from accidentally slipping either around the collar or toward the top thereof, as will be 25 more fully described hereinafter and claimed.

My object is to provide a standing collar which, while being adapted to retain the necktie, may be made of the usual amount of linen or other material necessary to afford proper 30 stiffness without adding to its expense for additional material due to the tie-holding features and which shall be neat and attractive in appearance, as well as durable and economical in use.

35 A further object is to provide extra stiffness throughout the lower portions of the collar, and especially about the ends of the collar-band, where the front buttonholes are situated.

40 These objects are fully attained in my invention.

Referring to the drawings, Figure 1 represents a perspective view of a collar made in accordance with my invention and having a 45 string-tie connected thereto; Fig. 2, an elevation of a portion of the collar; Fig. 3, a transverse vertical sectional view on the line X X of Fig. 2; and Fig. 4, a transverse vertical sectional view on the line Y Y of Fig. 2, but on 50 an exaggerated scale, to show the formation of

the tie-holding device and approximately as it would appear before being pressed down.

In the several figures like letters designate corresponding parts.

The collar A may be composed of any suitable material, as linen, and is made in the usual manner and of four-ply or other desired thickness, the characteristic features of my invention being that the lower portion of the collar is divided into substantially two separate 55 portions F and G, between which the band of the tie B is inserted, and which when bent around the neck, acting as a clamp, effectually prevents movement of the tie. The whole 60 inner portion and the outer upper portion are 65 made substantially the same as other collars, so that the outside a presents a neat appearance, while the inner part is continuous from end to end, the top and bottom having turned-in edges l l and stitching h h'. The outside 70 portion F and inside portion G are lined by a continuous piece doubled over to form the back n of the front F and the front m of the back portion G. At the top of the opening E the front m is stitched to the inside b, (indicated at v,) being at a suitable distance above 75 the bottom f of the collar to admit the breadth of a tie-band of any style desired.

At the center of the length of the collar the outside portion F is preferably cut away sufficiently on a semicircular line C to expose the face i of the inside portion G and button-hole and is finished by the stitching u, continuing from the line h'. The inside portion G is suitably sewed together at the bottom, 85 and the piece cut away at C may be suitably stitched to the inside G, forming a reinforced part, through which the buttonhole d is cut and worked in the usual manner.

At a short distance back from each end 90 buttonhole e e the outside portion F has a slit D, through which the tie emerges, and stitching k binds all the layers of the fabric together, providing a stiff front end, while the stitching t binds together only the layers 95 forming the outside portion F. The slits D extend from the bottom f to the top of the opening E.

It will be observed that while the outside portion F constitutes a tie-holding flap ex- 100

tending nearly the whole length of the collar the construction is such that when pressed for use any unevenness due to the division attaches to the inner portion, the outer face 5 *a* being smooth and neat in appearance and appearing like an ordinary collar, except where cut away at the center and at the slits, which, however, are usually hidden by an outer garment.

10 Having thus described my invention, what I claim as new, and desire to secure by Letters Patent, is—

15 The herein-described collar consisting of the inner and outer portions, and the intermediate lining portion folded longitudinally and stitched at one bottom edge to the inner portion and at the other bottom edge to the

outer portion, said outer portion and its lining having a slit near each end thereof and being stitched to said inner portion between 20 said slit and the adjacent end thereof and having the cut-away portion at the back or longitudinal center, said part which is cut out being stitched to said inner portion and its lining as a reinforcement, said inner portion and its lining being stitched together at the fold of said lining, substantially as shown and described.

25 In testimony whereof I affix my signature in presence of two witnesses.

MATTHEW B. KENDRICK.
